United States Patent Office

Des. 187,378
Patented Mar. 8, 1960

187,378

ADJUSTABLE RECORD FILE HOLDER

Carl J. Allen, East Cleveland, Ohio

Application November 13, 1958, Serial No. 53,365

Term of patent 14 years

(Cl. D33—3)

Fig. 4

Figure 2 is a side elevation view of my design;
Figure 3 is an end elevation of my design; and
sponding to Figure 1 with, however, the record holder adjusted to an intermediate position of receptivity.

I claim:

The ornamental design for an adjustable record file
holder, as shown.
